UNITED STATES PATENT OFFICE.

GERHARD SCHAGEN, OF ESCHWEILER, ASSIGNOR TO MAX HEYMANN, OF AIX-LA-CHAPELLE, GERMANY.

WRITING-PEN.

SPECIFICATION forming part of Letters Patent No. 530,604, dated December 11, 1894.

Application filed October 12, 1894. Serial No. 525,710. (No model.) Patented in England April 5, 1894, No. 6,824, and in Austria April 17, 1894, No. 44/1,040.

To all whom it may concern:

Be it known that I, GERHARD SCHAGEN, book-keeper, a citizen of the German Empire, and a resident of Eschweiler, in the Kingdom 5 of Prussia, Germany, have invented certain new and useful Improvements in Writing-Pens, of which the following is a specification.

My invention relates to improvements in writing-pens.

10 The new pen represented in the accompanying drawings possesses as compared with those hitherto in use the advantage that it takes up a greater quantity of ink whereby the great waste of time involved in frequent 15 dipping of the pen into the inkstand is materially diminished and at the same time a greater speed in writing is attained and greater durability in the pen. Moreover the risk of dropping blots from the pen is entirely 20 done away with by this invention.

In the accompanying drawings Figure 1 is a perspective view of my improved pen; Fig. 2, a top view, and Fig. 3 a side view of the same.

This improvement in the pen consists in a 25 tongue *a* (Figs. 1, 2 and 3) which, forming an integral part of the pen lies parallel to its back at a little distance therefrom and extends nearly to its point. This tongue is stamped out of the back part of the body of 30 the pen which is inserted in the pen-holder and bent forward into the position shown in

Figs. 1 and 3. The notch *b* at the end of the tongue which lies over the pointed part of the pen allows to slit its point in the ordinary manner, as the tongue during the process of 35 fabrication must be bent over before the point of the pen has been split. Owing to this disposition the ink is taken up and retained in greater quantity in the space between the tongue and the back of the pen, by capillary 40 attraction gradually flowing thence during use.

Having thus fully described my invention, what I claim, and desire to secure by Letters Patent, is—

45 In a writing-pen a tongue *a* formed in one piece with the pen, being stamped out of the back part of its body and bent over forward so as to lie parallel with its back at a short distance therefrom, this tongue which extends 50 nearly to the point of the pen being provided at the end with a notch *b* lying over the slit point of the pen, substantially as described and for the purpose specified.

55 In testimony that I claim the foregoing as my invention I have signed my name in presence of two subscribing witnesses.

GERHARD SCHAGEN.
